METHOD AND APPARATUS FOR DUPLICATING RECORDS

Wilhelm Ritzerfeld, Berlin, Germany

Application November 1, 1935, Serial No. 47,777
In Germany November 8, 1934

8 Claims. (CL 101—132)

The present invention relates to a method of sectionally or line-by-line copying on sheets, cards or the like and more particularly to such a method and such an apparatus, in which is copied from an original or master sheet, carrying reversed or mirror script, capable of transfer by impression, on sheets being previously moistened with a thin film of a readily volatilizing liquid.

Heretofore apparatus were known in which the original or master sheet is secured on a printing drum cooperating with a counter pressure roller. A pre-moistened sheet is fed to the contact line of the drum and the counter pressure roller and thus a copy is taken on the sheet.

In order to have copied single lines or sections, in front of the drum a moistening device of single line width is provided cooperating with a counter pressure roller of the same extension. By this contrivance single lines of the original or master sheet may be printed on pre-moistened sheets, cards or the like.

The object of the present invention is a method of sectionally or line-by-line copying just in the opposite way i. e. to take copies from a certain number of originals on a single sheet. This way of copying or duplicating is advantageously used for bookkeeping purposes, for material lists etc.

For this reason the sheet to be copied on is secured on a drum which is cooperating with a counter pressure roller. The copy on the sheet is taken from an original or master sheet being fed to the apparatus with its lines vertically to the axis of the drum.

The moistening device is provided in such a manner, that it may be controlled by a cam and periodically pivoted towards the sheet on the drum. For bookkeeping purposes the moistening device as well as the counter pressure roller are provided of single line's width. After each rotation of the drum the sideways displacing of the moistening device in connection with the counter pressure roller is effected automatically at the width of one line. By this method and by the apparatus for operating according to this method it is possible to copy lists from any desired number of originals or master sheets.

The drawing illustrates a side elevational view, having parts in section, of a duplicating machine embodying the principles of the present invention.

In the illustrated embodiment a main or printing roller 1 is rotatably mounted between the two side walls of a rigid machine frame. Print-

ing roller 1 cooperates with a counter pressure roller 3. A feeding table 4 is mounted in front of the bight of the printing and counter pressure rollers for introducing original sheets bearing copyable mirror-script in between the rollers. A clear copy sheet is tensioned around the circumference of the printing roller 1 by means of a clamping device 1'. In front of the printing roller 1 is provided a moistening device 2 slidably connected by means of a key and keyway to a rotatable spindle 7 and pressed in the direction of the printing roller by means of a spring 8. Spindle 7 also carries an actuating lever 5 rigidly connected thereto and carrying a small roller at its free end. The moistening device has a width of one or of a few lines and is actuated by means of a cam disc 6 having a nose extending towards the actuating lever 5 and attached to one of the sides of the printing roller 1. Conventional means (not shown) are also provided for displacing the moistening device and preferably also the counter pressure roller by the width of a single line on the spindle 7 in a direction parallel to the axis of the printing roller after each rotation of the printing roller in order to progressively moisten different portions of the clear sheet tensioned around the printing roller.

From the preceding description the operation of the novel duplicating apparatus will be readily understood by those skilled in the art. In direct contrast to the conventional procedure in which a copyable mirror-script original is tensioned around the printing roller, a clear or copy sheet is provided around the circumference of roller 1 and is fastened thereto by means of clamping bar 1'. In the normal position of rest of the apparatus, the nose on cam disc 6 engages the roller associated with actuating lever 5 and maintains moistening means 2 in an inoperative position against the pressure of spring 8. When the apparatus is started and roller 1 is rotated, actuating lever 5 will become disengaged and the moistening device will be pressed against the clear or copy sheet around the roller moistening a circumferential and restricted portion thereof. At the same time, a sheet bearing copyable mirror-script original is introduced on feed table 4 in between the bight of rollers 1 and 3 and will be pressed against the moistened copy sheet, so that a portion of the original corresponding to the moistened portion of the copy sheet will be permanently imprinted onto the copy sheet. After the first original has been recorded, the moistening device and preferably also the counter pressure roller are displaced in axial direc-

tion, for example, by the width of a single line, either manually or automatically so that the apparatus is ready for receiving and permanently recording the second original. This simple procedure is continued until all of the originals have been copied and recorded or the copy sheet has been filled with the matter selectively copied from the various original sheets. Thus, complex bookkeeping problems, material lists, wage lists and the like, may be handled in a simple and automatic manner and with an almost complete elimination of intellectual effort and of errors.

I claim:

1. In a duplicating apparatus printing onto clear sheets previously moistened with a readily volatilizing solvent, the combination comprising a rotatable printing roller, means associated with said printing roller for securing a copy sheet to be printed onto around the circumference thereof, a counter pressure roller cooperating with said printing roller to press a sheet bearing copyable mirror-script original against said copy sheet, and a moistening device adapted to be intermittently moved from an inoperative into an operative position to bear against the circumferential surface of said printing roller and to moisten said copy sheet secured around said printing roller.

2. In a duplicating apparatus printing onto clear sheets previously moistened with a readily volatilizing solvent, the combination comprising a rotatable printing roller, means associated with said printing roller for securing a copy sheet to be printed around the circumference thereof, a counter pressure roller cooperating with said printing roller to press a sheet bearing copyable mirror-script original against said copy sheet, a moistening device adapted to be displaced from an inoperative into an operative position to bear against the circumferential surface of said printing roller, and means associated with said printing roller for intermittently displacing said moistening device and to moisten said copy sheet secured around said printing roller.

3. In a duplicating apparatus printing onto clear sheets previously moistened with a readily volatilizing solvent, the combination comprising a rotatable printing roller, clamping means associated with said printing roller for tensioning a copy sheet to be printed onto around the circumference thereof, a counter pressure roller of substantially single line width cooperating with said printing roller to press a restricted portion of a sheet bearing copyable mirror-script original against said tensioned copy sheet, a pivotally displaceable moistening device of substantially single line width adapted to be displaced to bear against the circumferential surface of said printing roller, and means for displacing said moistening device from an inoperative into an operative position to engage and to moisten said tensioned copy sheet.

4. In a duplicating apparatus printing onto clear sheets previously moistened with a readily volatilizing solvent, the combination comprising a rotatable printing roller, clamping means associated with said printing roller for tensioning a copy sheet to be printed onto around the circumference thereof, a counter pressure roller of substantially single line width cooperating with said printing roller to press a restricted portion of a sheet bearing copyable mirror-script original against said tensioned copy sheet, a pivoted moistening device of substantially single-line width located in front of the bight of said rollers adapt-

ed to be displaced to bear against the circumferential surface of said printing roller, and means including a cam disk associated with said printing roller for intermittently displacing said moistening device from an inoperative into an operative position to engage and to moisten said tensioned copy sheet.

5. In a duplicating apparatus printing onto clear sheets previously moistened with a readily volatilizing solvent, the combination comprising a rotatable printing roller, clamping means associated with said printing roller for tensioning a copy sheet to be printed onto around the circumference thereof, an axially displaceable counter pressure roller of substantially single line width cooperating with said printing roller to press a restricted portion of a sheet bearing copyable mirror-script original against said tensioned copy sheet, a pivotally and axially displaceable moistening device of substantially single line width located in front of the bight of said rollers adapted to be pivotally displaced to bear against the circumferential surface of said printing roller, and means associated with said printing roller for pivotally displacing said moistening device to engage and to moisten said tensioned copy sheet.

6. In a duplicating apparatus printing onto clear sheets previously moistened with a readily volatilizing solvent, the combination comprising a rotatable printing roller, clamping means associated with said printing roller for tensioning a copy sheet to be printed onto around the circumference thereof, a counter pressure roller cooperating with said printing roller, means for introducing a sheet bearing copyable mirror-script original in between the bight of said rollers, a pivotally and axially displaceable moistening device of substantially single line width adapted to be pivotally displaced to bear against the circumferential surface of said printing roller, means pivotally displacing said moistening device toward said printing roller to engage and to moisten said tensioned copy sheet, and means associated with said printing roller for axially displacing said moistening device by the width of a single line after each revolution of said printing roller.

7. The method of copying a plurality of copyable mirror-script originals onto a single copy sheet previously moistened with a readily volatilizing solvent which comprises tensioning a clear sheet around the circumference of a roller, selectively moistening circumferential portions of said clear sheet, and successively passing a plurality of copyable mirror-script originals in contact with said clear sheet whereby selected portions of said originals will be collectively printed onto said single clear sheet.

8. The method of copying a plurality of copyable mirror-script originals onto a single copy sheet previously moistened with a readily volatilizing solvent which comprises rotating a clear copy sheet along a closed circular path, successively moistening selected portions of said clear sheet in the direction of rotation thereof, and successively pressing a plurality of original sheets in restricted contact with said rotated clear sheet, each of said original sheets bearing copyable mirror-script having its lines arranged in the direction of feeding said sheets whereby selected portions of said originals will be collectively printed onto said single clear sheet to form a tabulation thereon.
